WOOL WASHING MACHINE

Winfred W. Windle, Sutton, Mass.

Application March 12, 1934, Serial No. 715,184

3 Claims. (Cl. 141—5)

This invention relates to machines for washing or scouring wool or other similar fibers, and for removing grease and dirt therefrom. In such washing or scouring machines, the wool is fed loosely into an elongated tank partially filled with water or with a soapy or alkaline solution, according to the condition of the wool to be treated. The wool is loosely suspended in the solution and is gradually worked toward the delivery end of the machine during the washing operation.

It is essential that the wool fibers be gently handled while in the machine, as otherwise an undesirable felting action may take place, particularly when a soapy solution is used.

It has been customary in certain wool washing machines to use a mechanically operated rake for thus gradually advancing the wool along the tank. These rakes have been given a forward motion when in the solution and an idle reverse movement when raised out of the solution, so that the action has been intermittent and the feeding device has been inoperative more than one-half of the time.

It is the object of my invention to provide a wool washing machine having improved means for advancing the wool through the solution and for causing the wool to progress toward the discharge end of the tank.

A further object is to provide forwarding means which is continuous in its action, so that the wool is given a substantially uniform and continuous advance movement through the machine, instead of being alternately pushed ahead and brought to rest as in certain previous machines.

A still further object is to provide means for giving the wool an elongated path of travel through the machine, by introducing a transverse component into the forwarding action.

My invention further relates to arrangements and combinations of parts which will be herein-after described and more particularly pointed out in the appended claims.

A preferred form of the invention is shown in the drawings, in which

Fig. 1 is a plan view of portions of my improved wool washing machine;

Fig. 2 is a partial side elevation thereof;

Fig. 3 is a plan view of one of the forwarding members;

Fig. 4 is a sectional end elevation thereof;

Fig. 5 is a plan view of one of the paddles or blades;

Fig. 6 is a side elevation of the part shown in Fig. 5, and

Fig. 7 is a plan view of a modified forwarding member.

Referring to Figs. 1 and 2, my improved wool washing machine comprises an elongated tank 10, preferably rectangular in cross section and usually entirely open at the top. The tank is filled with water or other suitable liquid to a substantial depth, as shown in Fig. 2, and is preferably provided with a perforated screen or false bottom 11 which keeps the wool in the upper part 10 of the solution, while dirt removed from the wool may drop through the screen 11 and accumulate in the bottom portion of the tank, from which it may be occasionally removed as desired.

I have indicated a supply chute 12 at the left-hand end of the machine, as viewed in Fig. 2, through which chute the loosened fibers are dropped into the tank 10. Any suitable and usual mechanism may be provided for feeding the loosened fibers to the chute 12.

At the right-hand end of the machine, as viewed in Fig. 2, I have shown the perforated screen or false bottom 11 gradually approaching the surface of the solution in the tank and connecting with a guide-plate 14 which forms a continuation of the perforated screen 11 and guides the wool or fiber between a pair of press rolls 15 by which the wool is squeezed and delivered to a conveyor 16, which takes the wool to a second washer or to a drier according to the stage to which the wool treatment has progressed.

Suitable means is provided for delivering wool to the rolls 15, and in Figs. 1 and 2 I have shown the usual type of such mechanism.

As shown, the delivery mechanism comprises a rake 20 pivoted on a cross shaft 21, the outer ends of which are supported in bearings in blocks 22 provided with rolls 23 and slidable on inclined fixed guideways 24. Levers 26 (Fig. 1) are also pivoted on the shaft 21 and at their opposite ends are connected to an elongated crank portion 27 of a crankshaft 28, pivoted in bearing brackets 29 mounted on the tank 10.

The arms 26 are connected by links 30 (Fig. 2) to the rake 20. The crankshaft 28 is provided with a pinion 31 (Fig. 1) connected by an intermediate gear 32 to a drive gear 33. The crankshaft 28 is thus continuously rotated and the rake 20 is moved to the right while in lowered position and is returned to the left while in raised position, thus intermittently advancing the wool to the press rolls 15.

This delivery mechanism is illustrative only and forms no part of my present invention, which

relates more particularly to the construction of the forwarding members by which the wool is advanced through the solution in the tank 10.

Each of these forwarding members comprises 5 a body portion or barrel 40 (Figs. 3 and 4) mounted on a shaft 41 supported in brackets or bearing blocks 42 on the top edges of the tank 10. Any convenient means may be provided for continuously rotating the shaft 41 and in Fig. 1 10 I have shown the shaft 41 provided with a sprocket 44 engaged by a drive chain 45.

It will be understood that in practice the machines are very much elongated and that any desired number of forwarding members may be 15 provided. The sprocket chain 45 may be arranged to engage sprockets 44 on all of the shafts 41 and thus simultaneously rotate all of the forwarding members. Preferably the chain 45 is connected to a driving sprocket operated in 20 timed relation to the movement of the drive gear 33.

The barrel 40 of each forwarding member is provided with a plurality of blades or paddles 50 (Figs. 3 to 6). These blades are arranged in a 25 plurality of longitudinally extending series on the barrel 40. The blades 50 in one series are somewhat sharply inclined to the axis of the barrel 40 in one direction and the blades 50^a of the next series are correspondingly inclined in 30 the opposite direction.

The shape of the blades may be varied but is preferably substantially as indicated in Fig. 6, so that the bottom of the blade fits the polyangular surface of the barrel 40, while the top of the 35 blade is provided with a beveled leading outer corner 51 and with a beveled leading edge 52. The rear outer corner is preferably rounded as indicated at 53.

The blades 50^a are similar to the blades 50 except that the beveled leading edge 52^a (Fig. 3) 40 is oppositely disposed. The blades 50 may be firmly secured to the surface of the barrel 40 in any desired manner, as by angle brackets 60 (Fig. 3).

The operation of my improved machine will 45 be readily understood. By continued rotation of the forwarding members, the blades or paddles 50 and 50^a thereon are successively submerged and advanced through the water toward the right 50 or delivery end of the machine, thereby gently urging the suspended wool in the desired direction.

Furthermore, as the blades of successive series 55 are oppositely inclined, the wool is first pushed transversely toward one side wall of the tank 10 and then transversely toward the opposite side wall, thus progressing along a more or less zig-zag path of travel.

The length of travel is further substantially 60 increased by the action of the blades in producing limited whirlpool effects in the water, as indicated by the arrows in Fig. 1. As the wool passes beyond the field of action of one forwarding member, it comes into the field of action of the 65 next forwarding member and is thus given a substantially continuous although somewhat irregular advance movement toward the delivery end of the machine.

I sometimes find it desirable to mount spray 70 pipes 70 (Fig. 1) between successive forwarding members, and these spray pipes are provided with perforations which are inclined downwardly and rearwardly, so that water will be delivered therefrom as indicated in Fig. 2. These rearwardly and downwardly directed jets of water

serve to further agitate the wool in the solution and also tend to submerge the wool to greater depth, it being found that the wool has a tendency to float at or near the surface of the solution.

The spray pipes may also be used to vary and control the rate of travel of the wool through the tank as the rearward direction of the jets tends not only to agitate and submerge the wool, but also to retard its travel toward the delivery 10 end of the machine. Thus by increasing the force of the jets, the rate of travel of the wool may be correspondingly decreased and the time 15 of the washing operation may be lengthened when desired.

In Fig. 7 I have indicated a modified construction of forwarding member which is well adapted 20 for construction from suitable sheet metal. This modified forwarding member 90 comprises a deeply corrugated metal barrel mounted on a suitable drive shaft 91. The corrugations of the member 90 are oblique to the axis of the shaft 91, however, so that different portions of the corrugations produce transverse components of action 25 alternately disposed as in the form previously described.

With the modified forwarding member shown 30 in Fig. 7, the wool is pushed gently first toward one side wall and then toward the other wall, at the same time advancing toward the delivery end 35 of the machine, all as previously described.

In practical operation, it has been found that a wool washing or scouring machine equipped 40 with my improved forwarding members will effectively remove dirt or other foreign substances from the wool without felting action, and will accomplish this at a very substantially increased speed, so that substantially more wool can be passed through the machine in a given length of 45 time.

My improved machine is also extremely simple, comprising many less parts than the commonly 50 used rake feeding mechanism, and there are no relatively moving parts which are liable to become loosened or get out of adjustment.

The modified construction shown in Fig. 7 55 forms the subject matter of a divisional application Serial No. 48,083, filed by me November 4, 1935.

Having thus described my invention and the 60 advantages thereof, I do not wish to be limited to the details herein disclosed, otherwise than as set forth in the claims, but what I claim is:—

1. A wool washing machine comprising an 65 elongated tank to contain a washing solution and a plurality of driven forwarding members each rotatably mounted on said tank, each forwarding member extending transversely of said tank and having a plurality of rows of peripheral 70 wool-engaging portions, said portions in one row being angularly displaced in a clockwise direction from coincidence with a plane perpendicular to the axis of said forwarding member and said 75 wool-engaging portions in an adjacent row being similarly angularly displaced but in a reverse direction.

2. A wool washing machine comprising an 80 elongated tank to contain a washing solution and a plurality of driven forwarding members each 75 rotatably mounted on said tank, each forwarding member extending transversely of said tank and having a plurality of separate peripherally disposed 85 wool-engaging blades arranged in a plurality of adjacent axially extended series, the 90

blades in one series being angularly displaced in a clockwise direction from coincidence with a plane perpendicular to the axis of said forwarding member and the blades in the next adjacent series being similarly angularly displaced but in a reverse direction.

5. A wool washing machine comprising an elongated tank to contain a washing solution, and a plurality of driven forwarding members each 10 rotatably mounted on said tank, each forwarding member extending transversely of said tank and comprising a plurality of wool-engaging blades

arranged in successive axially adjacent series, the blades in one series being angularly displaced in a clockwise direction from coincidence with a plane perpendicular to the axis of said member and the blades of the next adjacent series being oppositely displaced with respect to said plane, and the blades in any one axial series being out of circumferential alignment with the blades in the next adjacent series at both sides of said axial series. 10

WINFRED W. WINDLE.
